UNITED STATES PATENT OFFICE.

EDWARD W. McGINLEY, OF PHILADELPHIA, PENNSYLVANIA.

LOCKING MECHANISM.

Application filed December 23, 1926. Serial No. 156,733.

One object of my invention is to devise a novel construction of a locking mechanism which is adapted to be employed to lock any desired mechanism.

- 5 Another object of my invention is to devise a novel lock which can be set for any desired key, and wherein the actuation of an improper key will prevent the unlocking of the lock.
- 10 Another object of my invention is to devise a novel locking mechanism for automobiles which will lock the gear shifting lever of a motor vehicle in its neutral position irrespective of the position in which it is located, said locking mechanism being preferably controlled by the opening of a door of the motor vehicle.
- 15 With the above and other objects in view as will hereinafter more clearly appear, my invention comprehends a novel locking mechanism.

20 Other novel features of construction and advantage will hereinafter clearly appear in the detailed description and the appended claims.

25 For the purpose of illustrating the invention, I have shown in the accompanying drawing a typical embodiment of it, which, in practice, will give reliable and satisfactory results. It is, however, to be understood that this embodiment is typical only and that the various instrumentalities of which my invention consists can be variously arranged and organized, and that the invention is not, therefore, limited to the precise arrangement and organization of these instrumentalities as herein set forth.

30 Figure 1 is a top plan view of a locking mechanism, embodying my invention.

35 Figure 2 is a section on line 2—2 of Figure 11.

Figure 3 is a side elevation of a bottom locking lever.

40 Figure 4 is a side elevation of a top locking lever.

Figure 5 is a bottom plan view of the locking mechanism.

45 Figure 6 is a section on line 6—6 of Figure 1.

50 Figure 7 is a top plan view of a locking member and certain of its adjuncts.

Figure 8 is a side elevation of a key.

55 Figure 9 is a section on line 9—9 of Figure 8.

Figure 10 is a bottom plan view of a key showing one of the arrangements which can be employed.

Figure 11 is a section through the locking mechanism and the motor vehicle transmission, on line 11—11 of Figure 2.

Figure 12 is a diagrammatic view showing its control by the doors of a motor vehicle.

Similar numerals indicate corresponding parts.

Referring to the drawings:—
The supporting frame work or housing may vary widely in construction, and for convenience of illustration I have shown it as consisting of a casing 1, to which is secured a bottom plate 2 by means of rods 3 passing through the top of the casing and in threaded engagement with the bottom plate. It will be noticed that these fastening rods 3 do not pass through the bottom plate and the casing is counter sunk to receive the heads of the rods so that molten metal may be poured in to cover the heads after the rods have been screwed in a position so that it is practically impossible to tell from the appearance of the casing or housing the manner in which it is secured together.

70 The locking mechanism is concealed within the casing 1 and is supported on a pair of plates 4 which are fixed to a bottom plate 5 having a longitudinally extending recess 6, see more particularly Figure 11, in which is mounted to slide in opposite directions the slides 7.

75 As each slide and its adjuncts is of the same construction, I have, for the sake of brevity, described in detail the construction of but one of these slidable units.

80 Referring now more particularly to Figure 7, it will be seen that each of the sliding locking mechanisms consist of a slide 7 in the form of a plate having a predetermined number of apertures 8, the purpose of which will hereinafter clearly appear. Each slide 85 7 is connected at its outer end to a cross bar 9 to which may be connected, if desired, and in any desired manner, an actuating rod 10. Each cross bar 9 has fixed to it guide rods 100 11 which pass through the deflected aperture ears 12 of the guide brackets 13.

85 In order to provide for the simultaneous movement in opposite directions of the slides

7, each bar has connected to it the rods 14 which at their inner ends are pivotally connected to levers 15 loosely mounted on stud shafts 16 carried by the supporting plates 4 and extending laterally therefrom. Each cross bar 9 is provided with a locking member 17 and one of these is off-set so that it will slide beneath the other. Each locking member is provided with a recess 18, the inner end of which is rounded, and from this rounded portion, the opposite side of the walls of the recess diverge toward the end of the locking member 17 as indicated at 19.

The slides 7 are retained in position by means of a top plate 20 which is secured to the bottom plate 5 by means of fastening devices 21, see Figure 1. The bottom plate 5 has connected with it as illustrated, bottom brackets 22 through which pass rods 23 which serve as fulcrums for a series of levers 24 having pivotally connected with them locking pins 25. These levers 24 have pivoted to them at their free ends, the rods 26 which pass through a line of apertures 27 in the bottom plate 5 and the top plate 20, and are connected with the arms 28, from which extend upwardly the pins 29.

These arms 28 are in threaded engagement with their rods 26 and between such arms and the top plate 20 are interposed springs 30 which tend to maintain the pins 29 and their adjuncts in their raised position.

The locking pins 25 of the levers 24, are adapted to pass through apertures 31 in the bottom plate 5 and if an aperture 8, in the plate 7 registers therewith, it will pass through such registering aperture 8 and retain a slide 7 in its locked position. These levers 24 and locking pins 31, I term for the purpose of description, as the bottom locking levers and locking pins.

The top plate 20 is provided with brackets 32 through which pass the rods 34 which serve as fulcrums for sets of top levers 35 having locking pins 36 pivotally connected to them and adapted to pass through apertures 37 in the top plate 20 and registering aperture 8.

These levers 35 have connected to their free ends the locking pins 38 which extend above and below their levers so that the lower portion is adapted to enter the line of apertures 27 in the top plate 20 and the bottom plate 5 respectively. Between the top plate 20 and the levers 35 are interposed springs 39 which tend to maintain the locking pins 36 in their unlocked position.

The locking rods 38 have adjustably connected with them the arms 40, and as illustrated, the arms 40 are in threaded engagement with the upper ends of the rods 38.

The arms 40 are connected at their free ends with upwardly extending pins 41. The pins 41 and 29 may be called key pins and

are contained within a sleeve 42. Surrounding this sleeve is a spring 43, the function of which is to eject the key 44 when the operator removes his hand from the key so that the key will not be retained in the space 45, see Figure 6, formed by the upward extending apertured boss of the top face of the casing 1, as will be understood by reference to Figures 2 and 6.

The sleeve 42 is provided with the ribs 46, see Figures 1 and 2, and the sleeve 47 of the key is provided with slots 48. Contained within the sleeve 47 are the key pins 49 which are fixed in a block 50, secured in any desired manner within the sleeve, and the sleeve is surrounded by a collar 51 from which extends a plate 52 which forms a grasping handle.

The casing 1 is provided with an extension 53 having a tapered opening through it in order to be adapted to fit over a corresponding tapered portion of the housing 54 of the transmission of the motor vehicle, and such portion of the transmission housing of the extending casing 53, is apertured at 55 in order to receive the locking plates 17, which are adapted to lock the gear shift lever 56 of the transmission in its neutral position, irrespective of the position to which it has been moved by the operator.

It is one of the objects of this invention to provide a locking mechanism which can be controlled by the doors of the automobile, such as, for example, the doors providing access to the driver's seat, so that the opening of such door or doors will automatically move the gear shift lever 56 to its neutral position and lock it in such position, due to the action of opening the doors through an intermediate mechanism operatively connected with the actuating rods 10, moving the slides 7 into such position that their apertures 8 will register with one or more of the locking pins and thus cause the locking mechanism to be positively locked.

The connecting means between the doors 57 and the rods 10 to cause the slides 7 to move toward each other may vary widely in practice, and for the purpose of illustration, I have shown the doors 57 as provided with the hooks 58, which during the opening movement of a door 57 are adapted to engage the upwardly extending rods 59, carried by the levers 60 fulcrumed at 61. A link 62 is connected at one end to a lever 60 and is connected at its opposite end to the links 63 and 64. The link 64 has a fixed pivot 65, and the link 63 is pivotally connected with its actuating rod 10.

It will thus be seen that if a door, leading to the driver's seat is opened, the hook 58 cooperating with the rod 59 will cause the link 62 to be moved laterally thereby forcing a rod 10, its slide and adjuncts, into locking position. The slides 7 are connected to move

in unison as before explained so that when one slide is operated it will effect the actuation of the other slide.

This movement towards each other of the slides 7 into their locking position causes the locking member 17 to move toward each other so as to embrace the gear shift lever 56 and due to the outwardly diverting walls 19, it will be apparent that irrespective of the position in which this gear shift lever may have been moved, this movement toward each other of the locking plates 17 will bring the gear shift lever into its neutral position, if it is not in such position, and will positively lock it in its neutral position.

This is of special importance in connection with motor vehicles since the majority of automobiles which are stolen have been left in an unlocked position, and in accordance with this invention, it is impossible for a door affording communication to the driver's seat to be opened without locking the clutch lever in its neutral position.

The outward movement of the slide 7 and its adjuncts, or in other words the unlocking movement of the locking mechanism when the locking pins are released, is due to the provision of springs 66 interposed between the bars 9 and the apertured ears 12 of the brackets 13, these springs being carried by the guide rods 11 as will be clearly seen from Figures 1 and 5.

In Figure 10, I have shown the key as arranged for one arrangement, and if any other arrangement is provided, it will be impossible to effect the unlocking of the locking mechanism, or if the parts are in their locked position and an unauthorized person should press down a key pin 41 which does not form a part of the predetermined arrangement, it will be apparent that a locking pin 36 will enter an aperture 8 in a slide 7 so that the locking mechanism will not become unlocked.

It will also be apparent that in case an unauthorized person uses the key 44, seen in Figure 10, and in addition a pin which will actuate one of the locking pins 36, that while the lower locking pins 25 would release the slide 7, the upper locking pins 36 would enter apertures 8 in the plate 7 and prevent the unlocking movement of the locking member 17.

If the key pins 49 of the key are of the proper arrangement to contact with the key pins 26, it will be apparent that if the proper key for which the key pins 29 are arranged is inserted, that the locking pins 25 will be released and the springs 66 will cause the bars 9 and their adjuncts to move outwardly thereby moving the locking members 17 into their locked position.

Having thus described my invention what I claim as new and desire to secure by Letters Patent, is:—

1. The combination with the transmission of a motor vehicle and a door controlling access to the driver's seat, of locking mechanism controlled by the opening of said door and effective to automatically lock said transmission in its neutral position irrespective of the position in which it has been set. 70

2. The combination with the transmission of a motor vehicle, and doors controlling access to the driver's seat, of locking mechanism controlled by the opening of either of said doors to automatically lock said transmission in its neutral position, said doors being free to be opened and closed when the locking mechanism is locked without affecting its locked condition. 75

3. The combination with the gear shifting lever of a motor vehicle and a door controlling access to the driver's seat, of means controlled by the opening of said door to lock said lever in its neutral position, said door being free to be opened and closed when said lever is locked. 80

4. The combination with the gear shifting lever of a motor vehicle and a door controlling access to the driver's seat, of means controlled by the opening of said door to move said lever into neutral and to lock it in neutral. 90

5. The combination with the gear shifting lever of a motor vehicle, and a door leading to the driver's seat, of locking mechanism actuated by the opening of said door to lock said lever in its neutral position, and said door being thereafter free to close 100 and open without affecting said locking mechanism until the latter has been released.

6. The combination with the transmission of a motor vehicle, of a key controlled lock to unlock said transmission, and means controlled by a door of said motor vehicle to automatically lock said transmission in its neutral position. 105

7. In a locking mechanism, a body portion, a slide within said body portion, a locking plunger operatively connected with said slide, said body portion and slide having registering apertures when the slide is in its locked position, locking pins to enter said apertures, key control pins to control said locking pins, and resilient means to move said slide into its unlocked position. 110

8. In a locking mechanism, a body portion, a plurality of slides mounted within said portion to move in opposite directions when released, said body portion and slides having registering apertures when the slides are in locking position, locking pins to enter said apertures and adapted to be unlocked by a key, and resilient means to retain the 120 pins in locked position. 125

9. In a locking mechanism a body portion, a slide slidably carried by said body portion, said slide and body portion having registering apertures when in locked posi- 130

tion, a locking member connected with said slide to be actuated thereby, locking pins adapted to enter certain of said apertures, resilient means to retain said locking members in locked position, said locking members being adapted to be released by a key, a second set of locking members adapted to enter certain of said apertures, resilient means to retain said second set in unlocked position, and locking pins disposed in proximity to said key combination control whereby if the locking members of the first set are released and one of said locking pins is actuated to operate one of the locking members of the second set, the locking mechanism will still be retained in its locked position.

10. In a locking mechanism, a body portion, plates slidably carried thereby, said body portion and plates having registering apertures when the plates are in locking position, locking members actuated by said plates, bottom levers having locking members to enter said apertures, key controlled locking pins connected with said levers to actuate them, resilient means tending to move said locking levers and thereby their locking pins into their locked position, an upper set of levers, locking members carried by said upper set of levers and adapted to enter certain of said apertures, key controlled locking pins connected with said upper set of levers to actuate them, all of said locking pins being assembled in close relation to adapt them to receive a key having pins to cooperate with them.

11. In a locking mechanism, a body portion, a sealed casing within which said body

portion is located and provided with a key receiving opening; plates slidably carried by said body portion, said body portion and plates having registering apertures when the plates are in locking position, locking members exteriorly of said casing and operatively connected with said plates, bottom levers suitably fulcrumed and having locking members to enter certain of said apertures, key controlled pins located at said key receiving opening and operatively connected with said levers, springs tending to move said levers into the locking position of said locking members, upper levers suitably fulcrumed and having locking members to enter certain of said apertures, springs tending to move said upper levers into the unlocked position of their locking members, key controlled locking pins for said upper levers located at said key receiving opening, and resilient means to effect the unlocking movement of said plates when released by their locking members.

12. In a locking mechanism, a body portion, a slide movably carried by said body portion, said body portion and slide having registering apertures when the slides are in locking position, resilient means to move the slides into their unlocked position, locking pins to enter registering apertures, pin carriers having key controlled pins operatively connected with them, and a sleeve within which said key controlled pins are disposed and having means to position a key for cooperation with said key controlled pins.

EDWARD W. McGINLEY.
